[57] CLAIM

The ornamental design for a lipstick, as shown and described.

DESCRIPTION

FIG. 1 is a perspective view of a lipstick showing our new design;

FIG. 2 is a left side elevational view thereof, the side opposite being a mirror image of the side shown;

FIG. 3 is a front elevational view thereof;

FIG. 4 is a rear elevational view thereof;

FIG. 5 is a top plan view thereof; and,

FIG. 6 is a bottom plan view thereof.

The dark stippling in FIGS. 1, 3 and 5 represents a color contrasting surface.

FIG. 1

FIG. 3

FIG. 5

FIG. 2

FIG. 6

FIG. 4
